UNITED STATES PATENT OFFICE

1,972,636

DRILLING APPARATUS

Eugene Whinnen, Republic, Mich., assignor to
Sullivan Machinery Company, a corporation of
Massachusetts

Original application January 5, 1932, Serial No.
584,829. Divided and this application May 23,
1933, Serial No. 672,454

11 Claims. (Cl. 254—29)

This invention relates to drilling apparatus, and more particularly to improvements in a snubbing device for the drill rod line of a drilling apparatus of the oil and gas well type.

5 An object of this invention is to provide an improved drill rod line controlling means for a drilling apparatus. Another object is to provide an improved rod line snubbing device. A further object is to provide an improved rod line snubbing device having improved rod line gripping means and improved operating means for the gripping means. Still another object is to provide an improved mounting means for the rod line gripping means. Yet another object is 15 to provide an improved snubbing device for the rod line of an oil and gas well drilling apparatus whereby axial movement of the rod line in either direction may be controlled, the snubbing device automatically preventing upward movement of 20 the rod line and having cooperating means whereby, through the gripping means, the rod line may be forced into the drill hole against the opposing subterranean oil and gas well pressures. A further object is to provide and im- 25 proved rod line snubbing device for moving the rod line into the drill hole and withdrawing the rod line from the hole under constant control and while subjected to a relatively high subterranean pressure. These and other objects 30 and advantages of the invention will, however, subsequently more fully appear.

In the accompanying drawing there is shown for purposes of illustration one form which the invention may assume in practice.

35 In this drawing,—

Fig. 1 is a side elevational view of the illustrative form of the improved rod line snubbing device.

Fig. 2 is a bottom plan view of the snubbing device shown in Fig. 1.

Fig. 3 is a vertical sectional view taken substantially on line 3—3 of Fig. 2.

Fig. 4 is a detail vertical sectional view taken substantially on line 4—4 of Fig. 3.

45 Fig. 5 is a cross sectional view taken substantially on line 5—5 of Fig. 4.

In this illustrative embodiment of the invention, which is a division of my copending application Serial No. 584,829, filed Jan. 5, 1932, 50 the improved rod line snubbing device generally designated 1 comprises a frame 2 having attached thereto at its opposite ends suitable eyes 3, 3 for engagement with a "snubbing" line and suitable lug and bolt connections 4, 4 for engagement with a "catline" tie, the catline tie and

snubbing line herein arranged in the manner clearly described in the copending application above mentioned. The frame 2 of the snubbing device comprises a body 5 having attached thereto oppositely projecting arms, herein in the form of I-beams 6, 6. Formed in the body 5 is a chamber 7 of tapered form having its side walls converging upwardly in the manner shown in Fig. 3. In this chamber is a plurality of wedge-shaped rod line gripping jaws or slips 8, herein 60 four in number, having tooth-like serrations 9 on their inner faces for gripping the rod line, and these jaws are normally maintained in their released or spread-apart position by coiled springs 10 interposed between the jaws, as shown 65 in Fig. 5. These jaws are each grooved at 11, and engaging these grooves is a shifter collar 12 having trunnions 13 pivotally connected to a shifter yoke 14. This yoke is pivotally connected at 15 to a bracket 16 attached to the 70 bottom of the adjacent I-beam 6, and carries at its outer end an eye 17 to which there is connected an operating or "jerk" line 18. Pivotally connected to the trunnions 13 of the shifter collar at opposite sides of the jaw body 5, as shown 75 in Fig. 4, are eye-bolts 19 guided within perforated ears 20 formed on the sides of the jaw body and normally held in their raised position by coiled springs 21. These eye-bolts and 80 springs normally maintain the jaws 8 in their 85 upper rod line gripping position. Secured to the shifter yoke 14 is a guide plate 22 having formed therein a slot 23 in which is guided a pin 24 carried by a pivoted latch 25. This latch is pivoted at 26 on a bracket 27 attached to the 90 bottom of the adjacent I-beam 6 of the snubbing frame. Formed at one end of the slot 23 is a notch 28, and when the shifter yoke is in its lowermost position, as indicated in dotted lines 95 in Fig. 1, the pin 24 of the latch drops into the notch 28 to maintain the shifter yoke and gripping jaws in their lowermost released position. This latch may be released simply by pulling quickly downwardly on the operating line 100 18 to cause the pin 24 to jump out of the notch 28.

The improved rod line snubbing device is utilized to prevent jumping of the rod line upwardly from the drill hole without proper control while subjected to a relatively high subterranean pressure and for lowering the rod line into the hole against the opposing pressure. Let it be assumed that the rod line is being withdrawn 105 from the hole under high subterranean pres- 110

sure. The snubbing device when in its operating position is suspended by the catline of the drilling apparatus with the snubbing line attached to the eyes 3, 3 of the snubbing frame. 5 The snubbing device is then lowered by paying out the catline, and when the snubbing device is positioned above the upper end of the rod line the operator pulls on the operating line 18 to release the jaws 8, thereby enabling the snubbing device to be slid down over the rod line. When 10 the snubbing device is in position on the rod line, the operator releases the operating line 18 and the jaws 8 then engage the rod line. The hoisting tackle of the drilling apparatus is then 15 operated to take up any slack in the snubbing line, thereby to hold the snubbing device in position. Upon any tendency of upward movement of the rod line from the drill hole by the 20 pressure in the well, the jaws of the snubbing device tightly grip the rod line and hold the same against such movement. The snubber is held down by the snubbing line associated with the hoisting mechanism of the drilling apparatus, and is held in position thereby, and as a 25 result the rod line cannot move out of the hole. The hoisting tackle of the drilling apparatus is then operated to slacken up on the snubbing line, to permit movement of the snubbing device upwardly, thereby allowing the pressure in 30 the well to force the rod line out of the hole under the control of the snubbing device. Conversely, if it is desired to force the rod line into the hole against the opposing subterranean pressure, this may be accomplished by 35 slackening up of the catline connected to the bolt and lug connections 4, 4 of the snubber frame, while the hoisting mechanism is operated to move the snubber frame downwardly, thereby causing the snubbing device, together with the 40 rod line, to be forced downwardly against the opposing subterranean pressure by power sufficiently to overcome the opposing pressure. The jaws 8 of the snubbing device may be released 45 at will simply by pulling on the operating line 18 to move the shifter yoke into its lowermost position, the shifter yoke being held in this position by the latch 25.

As a result of this invention, it will be noted 50 that an improved rod line controlling mechanism is provided, whereby the rod line of an oil and gas well drilling apparatus may be moved into and out of the drill hole under constant control and while subjected to relatively high subterranean pressure. It will further be noted that 55 an improved rod line snubbing device is provided, of an extremely simple and rugged design and having improved mounting and operating means for the gripping jaws. These and other uses and advantages of the improved rod line snubbing device will be clearly apparent to those 60 skilled in the art.

While there is in this application specifically 65 described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rod line snubbing device, a frame having a chamber, snubbing jaws arranged in said chamber, yieldable means for normally maintaining said snubbing jaws in their operative po-

sition, and means for simultaneously releasing said snubbing jaws at will against the action of said yieldable means comprising a release lever pivoted on said frame and connected to said jaws.

2. A rod line snubbing device comprising a frame, supporting connections on said frame, controlling connections on said frame for bodily moving said frame, said frame having a chamber therein, snubbing jaws arranged in said chamber, yieldable means for normally maintaining said snubbing jaws in their operative position, and means for simultaneously releasing said jaws at will against the action of said yieldable means comprising a release lever pivoted on said frame and connected to said jaws.

3. A rod line snubbing device comprising a casing having a chamber therein, snubbing jaws arranged in said chamber, yieldable means for normally maintaining said jaws in their uppermost operative position, and means for simultaneously moving said jaws downwardly at will to release the same against the action of said yieldable means comprising a lever pivotally mounted on the bottom of said casing and a cooperating member pivotally connected to said lever and engaging all of said jaws.

4. In a rod line snubbing device, a frame having a chamber having its side walls converging upwardly, wedge-shaped snubbing jaws arranged in said chamber, yieldable means for normally maintaining said snubbing jaws in their raised rod line gripping position, and means operable at will for simultaneously moving said snubbing jaws downwardly to release the same from the rod line against the action of said yieldable means comprising a lever pivotally mounted on the bottom of said frame and a cooperating member pivotally connected to said lever and engaging all of said jaws.

5. A rod line snubbing device comprising a frame, supporting connections on the frame, controlling connections on the frame for bodily moving the latter, said frame having a tapered chamber therein having its inclined side walls converging upwardly, wedge-shaped snubbing jaws arranged in said chamber, yieldable means for normally maintaining said snubbing jaws in their raised rod line gripping position, and means operable at will for simultaneously moving said jaws downwardly to release the same from the rod line against the action of said yieldable means including a lever connected to an element of said yieldable means.

6. A rod line snubbing device comprising a casing having a tapered chamber therein, the inclined side walls of which converge upwardly, wedge-shaped snubbing jaws arranged in said chamber, means for normally maintaining said jaws in their raised rod line gripping position, and means for simultaneously moving said jaws downwardly at will to release the same from the rod line against the action of said yieldable means including a lever connected to an element of said yieldable means.

7. In a rod line snubbing device, a frame having a chamber, snubbing jaws arranged in said chamber, means for normally maintaining said snubbing jaws in their operative snubbing position, means cooperating with elements of the first mentioned means for releasing said snubbing jaws at will, and means associated with said releasing means and comprising a locking element engageable with an element of said re-

leasing means for holding the latter in its jaw releasing position.

8. In a rod line snubbing device, a frame having a chamber, snubbing jaws arranged in said chamber, means for normally maintaining said snubbing jaws in their operative snubbing position, means for releasing said snubbing jaws at will including a pivoted operating lever, and means associated with said releasing means for holding the latter in its jaw releasing position including a latch pivotally mounted on the snubber frame and engaging the jaw operating lever.

9. A rod line snubbing device comprising a casing having a tapered chamber therein, the inclined side walls of which converge upwardly, wedge-shaped snubbing jaws arranged in said chamber, yieldable means for normally maintaining said jaws in their raised rod line gripping position, and means for simultaneously moving said jaws downwardly at will to release the same from the rod line against the action of said yieldable means comprising a jaw moving member cooperating with elements of said yieldable means.

10. In a rod line snubbing device, a frame having a chamber, snubbing jaws arranged in said chamber, yieldable means for normally maintaining said snubbing jaws in their operative snubbing position, means cooperating with an element of said yieldable means for releasing said snubbing jaws at will, and means associated with said releasing means comprising a locking element engageable with an element of said releasing means, for holding the latter in its jaw releasing position.

11. In a rod line snubbing device, a frame having a chamber, snubbing jaws arranged in said chamber, yieldable means for normally maintaining said snubbing jaws in their operative snubbing position, means for releasing said snubbing jaws at will including a pivoted operating lever, and means associated with said releasing means for holding the latter in its jaw releasing position including a latch pivotally mounted on the snubber frame and engaging the jaw operating lever.
